UNITED STATES PATENT OFFICE.

WILLIAM A. DUNN, OF SMITHVILLE, MINNESOTA, ASSIGNOR OF ONE-HALF TO A. M. MILLER, JR., OF DULUTH, MINNESOTA.

METHOD OF FINISHING BEAMS.

1,109,050.

Specification of Letters Patent.

Patented Sept. 1, 1914.

Application filed November 5, 1910, Serial No. 590,920. Renewed February 7, 1914. Serial No. 817,328.

To all whom it may concern:

Be it known that I, WILLIAM A. DUNN, a citizen of the United States, residing at Smithville, in the county of St. Louis and 5 State of Minnesota, have invented certain new and useful Improvements in Methods of Finishing Beams, of which the following is a specification.

This invention relates to an improved 10 method of finishing beams after the same have been treated in a shaping mill. My improved method consists in confining the beam between movable parts, during the period of finishing the products whereby the 15 molecules of metal are confined and shaped in such manner as to prevent the metal buckling which insures of the production of an accurate and properly alined beam. The method also comprehends improvements in 20 the various steps necessary to confine and hold the metal during the period of production of a beam.

In the drawings—Figure 1 is a side elevation partially in section of a mill constructed 25 in accordance with my invention. Fig. 2 is a partial plan view and horizontal section approximately on the line 2—2, Fig. 1, the caps of the set of rolls at the top of the figure being shown in position, while the caps 30 of the corresponding rolls at the bottom of the figure are omitted. Fig. 3 is a detail transverse section on the line 3—3 of Fig. 2, to illustrate the interior arrangement of the means for supporting one of the side vertical 35 rolls which coöperates with the set of web reducing rolls. Fig. 4 is a face view of one of the vertical side rolls shown in Fig. 3, and its supporting carriage. Fig. 5 is a plan view of the same. Fig. 6 is a detail 40 side elevation of the carriage, shown in Fig. 3. Fig. 7 is a detail transverse section on the line 7—7, of Fig. 2, to illustrate the interior construction of the mounting of one of the vertical rolls which coöperates with 45 the flange controlling set of rolls. Fig. 8 is a detail elevation of one of the rolls, shown in Fig. 7, and its supporting carriage. Fig. 9 is a detail plan view of the same. Fig. 10 is a side elevation of the said roll and its 50 carriage. Fig. 11 is a cross section on line 11—11, Fig. 2. Fig. 12 is a detail vertical section taken through the flange controlling rolls.

For the purpose of describing my improved method I will describe in detail the 55 mechanism disclosed in my copending application and executed of even date Serial No. 590,919.

Referring to the drawings, 1, indicates a foundation upon which the mill is mounted, 60 and supported thereon are guideways 2, and 3, in which are mounted two pairs of vertically disposed frames 4, and 5. The frames 4, and 5, are adjustably fixed to the guideways 2, and 3, by means of bolts indicated at 6.

In the vertical frames 4, the set of web reducing rolls 7 and 8 are mounted. The lower web reducing roll 7, is mounted in stationary bearings 9, while the upper web 70 reducing roll 8, is mounted in an adjustable bearing 10. The bearing 10, is formed with guideways to engage guides 11, on the inside of the frame 4, and at its upper end the said bearing has an upwardly extending screw 75 12, swiveled in the bearing and engaging a threaded opening in the vertical frame 4. On the upper end of the screw 12 is a worm gear 13. Depending from opposite corners of the bearing 10, are rods 14, connected at 80 their lower ends by a yoke 15, and pivotally connected to the yoke is a piston rod 16, the piston of which operates in a cylinder 17, secured to the underside of the frame 4. The construction just described, in reference to 85 the bearing 10, and its adjustment, it will be understood is duplicated on opposite sides of the roll 8, to insure that the said roll will be uniformly raised whereby to prevent irregularities in the product produced. 90 The web reducing rolls are of cylindrical formation and have their outer edges beveled as shown at 8^a, and are constructed exactly alike.

Mounted in guideways in the respective 95 vertical frames 4, are carriages 20, each of which carries a vertically mounted side roll 21, arranged adjacent the ends of the horizontal web reducing rolls 7 and 8. Each carriage 20 comprises a lower cup-shaped 100 member 22, and an upper member or cap 23, the latter being bolted, as indicated at 24, to the lower cup-shaped member 22. The two members 22 and 23 are formed with alined openings 24^a, to receive the journals 105 25, of a central hollow hub 26, which is

flanged to engage the surfaces of the two members 22, and 23, as shown clearly in Fig. 3.

The cap or member 23, is formed with a 5 shoulder 23^a, and an outwardly extending flange 23^b, the latter and the shoulder engaging the cup-shaped member 22, whereby when outward thrust is given the vertical roll 21, the shoulder 23^a, will abut against 10 the inner surface of the cup-shaped member 22, and transmit the strain on the journals to the frame. This hub is cored to form a chamber 27, with which communicates a water supply pipe 28, for the introduction 15 of water, which acts as a cooling medium when the mill is in operation, the water passing in at the bottom of the hub and overflowing through the top thereof. Fitted over the hub 26, is an adjustable tapered 20 bushing 29, keyed in position at 30, and on which the vertical roll 21, revolves. The cone-shaped bushing 29, may be adjusted vertically to properly center the vertical roll 21, by means of screws 31, which pass up 25 through threaded openings in the lower cup-shaped member 22. I have found by practical experience that once the cone-shaped bushing 29 is set, it has a tendency to wear on one side, due to the pressure exerted by 30 the metal passing between the periphery of the vertical roll 21, and the ends of the horizontal web reducing rolls 7 and 8. It is, therefore, necessary to provide means for overcoming this objection. I have provided 35 the upper journal 25, of the hub 26, with a series of grooves indicated at 35, and in the bearing 24^a, of the upper member 23 of the carriage, I have provided a groove 36, which may be brought into registry with 40 one of the grooves 35, to receive a pin 37, whereby to lock the hub and the cone-shaped bushing 29, in fixed position. Therefore, once the cone-shaped bushing 29, is set by the screws 31, and the pin 37, if it be desired 45 to change the position of said bearing 29, the pin 37 is withdrawn and a tool is inserted in the opening in the upper journal of the hub 25, and the cone-shaped bushing 29 and the hub 25 are given a quarter 50 turn to bring the next succeeding notch 35, into registry with the notch 36. The pin 37 is now inserted again, and a new surface of the cone-shaped bushing 29, is presented opposite the point where the greatest pressure 55 is exerted by the metal in passing through the mill.

The carriage 20, is formed with two annular oil receiving chambers 38, which are connected by an oil channel 39, oil being 60 supplied through an opening 40, whereby the cone-shaped bushing 29, may be thoroughly lubricated.

It is noted that according to my invention I use but a single side vertical roll 21, on 65 each end of the web reducing rolls 7 and 8,

and they are each in alignment with the other and are adjusted simultaneously toward and from the ends of the web reducing rolls 7, and 8. Each carriage 20, has swiveled to its outer end, two screws 42 engaging threaded openings 43 in bushings in the guide of the carriage 20. On the guideway are, fixed caps 44, each having an annular flange 45. The screws 42 pass through the caps and on the square ends of 70 the screws 42, fit worm gears 46. On the inner surface of the worm gears 46, are bolted plates 47, which engage behind the annular flanges 45, to retain the worm gears in proper position and form bearings for 75 the same. The worm gears 46, engage the worms 48, located on shafts mounted in bearings directly under the gears and the ends of said shafts are provided with beveled pinions 49 meshing with beveled pinions 50, on shafts 51, extending upwardly above the vertical frames 4, where said shafts 51 are provided with beveled pinions 52. It will, of course, be understood that the mechanism just described, is duplicated on 80 both sides of the mill, and a horizontal power shaft 53 is provided with beveled pinions 54, which engage the beveled pinions 52, and simultaneously operate the two carriages 20. On the shaft 53, are worms 54^a, 85 which engage with the worm gears 13, to raise and lower the bearings 10.

In the vertical frames 5, is a lower flange controlling roll 60, mounted in fixed bearings 61, and an upper adjustable flange controlling roll 62, mounted in a bearing 63, having guideways to engage guides 64, in the sides of frames 5. The bearings 63, have swiveled to them screws 64^a, engaging threaded openings in the frames 5, which 100 screws extend through the frame and are provided with squared ends on which fit worm gears 66. Extending from the lower corners of each of the bearings 63, is a rod 67, the respective pairs of rods being connected by a yoke 68, connected by a piston rod 69, with a hydraulic cylinder 70.

The flange controlling rolls have enlarged end portions indicated at 60^b, the outer edges of which are beveled at 60^b. Connecting the enlarged portions is a hub 60^c, and extending from the outer ends of the said rolls are flanges or hubs 60^d, designed to engage the edges of the flanges of the beam when passing through the mill. Adjacent each end of the flange controlling rolls is a carriage 72, in which is mounted a vertically disposed side roll 73, the periphery of which cooperates with the ends of the horizontal flange controlling rolls 60 and 62. 115

Each carriage 72, comprises a lower member 74, provided with a rib 75, and an upper member 76, which has a rib 77, designed to engage with the rib 75, to assist in locking two members together and resist the out- 120

ward strain of the pressure of the metal passing through the mill. Each member 74, and 76, has bolted to it a cap member 78, and a bearing is formed by said caps and 5 the two members, as indicated at 79 to receive the extended journals 80, of a hub 81, on which the vertical roll 73 is mounted. The vertical roll 73, is formed with depressions 82, on opposite surfaces and the members 74 and 76, are grooved as at 83. By 10 this construction I am enabled to obtain a substantial bearing for the journals of the hub 81, the groove 83, permitting of the enlarged outer portion of the vertical roll 73, 15 being seated within the carriage, as clearly shown in Fig. 7. The two members 74, and 76, of the carriage 72, are bolted together by bolts 85, so that the parts can be conveniently assembled and adjusted when 20 required.

Swiveled on the outer surface of each of the carriages 72, is a single screw 86, which is in the plane of the centers of the hub 81, and the flange controlling rolls 60 and 62, 25 and on the outer squared end of the screw 86, fits a worm gear 87. A hub 88 extends from the outer surface of the guide-way of the carriage 72, and at its outer end is formed with a flange 89, behind which fits 30 a ring 90, bolted to the inner side of the worm gear 87. The worm gear 87, meshes with a worm 91, mounted in bearings directly under the worm gear 87, and on one end of the worm shaft is a beveled gear 93, 35 and secured to a vertical shaft 94, mounted in bearings on the frame 5 is a beveled gear 93^a meshing with gear 93 and on the upper end of said shaft is a beveled gear 95. As stated, this mechanism is on both sides of 40 the mill so as to simultaneously adjust the two carriages 72.

A horizontal shaft 96, mounted above the vertical frame 5, has secured to it beveled gear wheels 97, which mesh with the beveled 45 wheels 95, and said shaft is also provided with a worm 98, which engages with the worm gear 66. Also on the shaft 96, is a beveled gear wheel 96^a, which is engaged by a beveled gear wheel 99, on a shaft 100, on 50 the opposite end of which is a beveled gear 101, meshing with a beveled gear on the horizontal shaft 53.

Supported on rods 105, and 106, mounted in openings 107, and 108, in the vertical 55 frames 4 and 5, is a bottom guide 109. The guide 109, is approximately flat on its upper surfaces and on its opposite edges it is provided with downwardly extending flanges 110, to correspond to the configuration of 60 the inner surface of the beam, as shown in Fig. 11. The ends of the bottom guide extend over the web reducing rolls and over the flange controlling rolls, as clearly indicated in Figs. 1 and 12. A front bottom 65 guide 111, extends forwardly from the web

reducing rolls and it is supported on a bar 112, which fits in openings 113, in the vertical frames 4.

114 indicates a top guide located in rear of the web-reducing rolls and it is mounted 70 on a shaft 115, and is counterbalanced by an arm and a weight 116. The weight is adjusted so as to keep the forward end of the guide 114, in constant contact with the top web reducing roll 8, and thus as the 75 roll is adjusted up and down, the guide will follow the same.

Fulcrumed on the shaft 115, is a top 80 guide 117 which extends rearwardly and is formed with an opening through which 85 passes the central portion of the upper flange controlling roll 62 as shown in Fig. 12, thus permitting the upper guide 117, to travel up and down with a top flange reducing roll. All of the guides are constructed so 90 as to correspond to the interior surfaces of the beam being rolled, but the space between the horizontal portions of the upper and lower guides is a trifle greater than the thickness of the web of the beam so as to 95 prevent the metal sticking. As the section of metal being rolled does not change its inside size, the guides will at all times properly guide the material to and from the rolls without the liability of side swaying or 100 twisting. Furthermore, the guides are so constructed that they guide the flanges of the beam as well as the web portions.

Short side guides 120, and 121, are located in front and rear of the web reducing 105 rolls, their ends being dovetailed at 122, and fitting in correspondingly shaped openings in the carriages 20, while their opposite ends are connected to rods 123, passing through lugs 124, on the vertical standards 105 4. The outer free ends of the rods 123, are threaded and are provided with nuts, as indicated at 125, the threaded portion passing through an opening in lugs 126 secured to the carriages 20. By this construction, both 110 ends of the side guides move simultaneously with the carriage.

In operation, a blank which has been previously treated in a shaping mill is entered 115 between the guides 120, to the web reducing rolls 7 and 8. The end flanges *a* of the beam fit in the space *b* formed between the ends of the web reducing rolls and the periphery of the vertical rolls 21, while the web portion *c* of the beam is operated upon by 120 the cylindrical portions of the web reducing rolls. The web reducing rolls are operated through the medium of suitable gears, which feed the beam toward the flange controlling rolls, the beveled portions 8^a of the web reducing rolls and the periphery of the vertical rolls 21 creating pressure sufficient to 125 shape the flanges of the beam, as shown in Fig. 3. As the beam passes from the web reducing rolls through the guides in rear of 130

the same, it is directed by the latter to the flange controlling rolls. The hubs 60^a on the flange controlling rolls are so arranged that they act upon the edges of the flanges *a* 5 of the beam, as shown in Fig. 7. The vertical rolls 73, are so situated, that the pressure exerted by the hubs 60^a on the flange *a* prevents buckling, and a substantially uniform flange is produced.

10 By providing the specific construction of the end vertical flange rolls 73, and their bearings, I am enabled to utilize a roll having the necessary strength and size to operate adjacent the two flange controlling rolls, 15 and at the same time I dispense with what has heretofore been used, *i. e.*, backing rolls and a saddle to carry the side rolls.

In the production of a beam according to the steps hereinbefore described, the web 20 and flanges of a beam are substantially confined between the web reducing rolls, and the side vertical rolls, which insures of a positive shape being imparted, and by the construction and arrangement of the guiding 25 means the beam is held in alinement during the period of its formation and for a definite period after leaving the flange controlling rolls, and its forward end is therefore prevented from bending laterally.

30 Again it is of the utmost importance at the time of the shaping of the metal by the web reducing rolls, that the friction between the shaping elements be reduced to a minimum, which is successfully overcome by the 35 provision of the end vertical rolls.

The second important step in my method consists in confining the metal flanges of the beam during the period they are passing between the flange controlling rolls. 40 Were it not for this step, experience has taught that the flanges become distorted and buckle, and therefore throws the surface of the beam out of alinement. But by providing a passageway the walls of which move 45 *i. e.*, the flange controlling rolls and the adjacent vertical rolls, the metal is rigidly held in bounds and is gradually compressed and confined to produce the necessary shape.

The third essential step in my method re- 50 sides in confining the beam between the time of the formation of the web, and the formation of the flanges. By maintaining the beam in a determined path, and holding in this path, the liability of uneven introduc-

tion to the flange forming rolls is entirely 55 dispensed with, and a beam of uniform and accurate size and shape is produced.

What I claim is:

1. The herein described method of rolling flanged beams, consisting in subjecting the 60 surfaces of the web of the beam to rolling pressure and simultaneously subjecting the outside surfaces and opposite edges of the flanges to rolling pressure, and holding the flanges of the beam in positive alinement 65 throughout the space of application of the rolling pressure and for a definite distance after the beam has received the rolling pressure by contact of guiding means with the inside of the flanges to prevent lateral bending 70 of the forward end of the beam.

2. The herein described method of producing flanged beams, consisting in subjecting the upper and lower surfaces of the web to rolling pressure and simultaneously there- 75 with subjecting the upper and lower edges of the flanges of said beam to rolling pressure at a different point in the length of the beam, subjecting the outer side surfaces of the flanges of the beam to inward rolling 80 pressure adjacent the points where the upper and lower surfaces of the web and the upper and lower edges of the beam are subjected to pressure, and holding the flanges of the beam in positive alinement through- 85 out the space of application of the rolling pressure and for a definite distance after the beam has received the rolling pressure by contact of guiding means with the inside of the flanges to prevent lateral bending of the 90 forward end of the beam.

3. The herein described method of rolling beams, consisting in subjecting the surfaces of the web of the beam to rolling pressure, and holding the beam in positive alinement 95 throughout the space of application of rolling pressure and for a definite space after the beam has received the rolling pressure by contact of guiding means with the inside of the flanges to prevent lateral bending of 100 the forward end of the beam.

In testimony whereof I affix my signature in presence of two witnesses.

WILLIAM A. DUNN.
